UNITED STATES PATENT OFFICE.

OLE SEVERSON, OF SHELTON, CONNECTICUT, ASSIGNOR TO THE O. K. TOOL COMPANY,
INC., OF NEW YORK, N. Y., A CORPORATION OF NEW YORK.

ADJUSTABLE COUNTERBORE.

Application filed December 9, 1924. Serial No. 754,740.

This invention deals with metal cutting tools and it aims, on the one hand, to overcome certain difficulties resulting from the reduction of size through wear and grinding, 5 and on the other hand, it seeks to accomplish certain improvements in respect to self-guiding features when the tool is to be arranged for counter-boring or counter-sinking operations.

10 Regarding the first consideration, it may be noted that heretofore various species of adjustable reamers have been proposed with the object of enabling worn teeth to be shifted into positions permitting additional 15 grinding without loss of size but such adjustments have usually been accomplished at the sacrifice of rigidity and simplicity in the tool. The aim of this phase of the invention is to provide for such an adjustment but to 20 do so in such a way that the tool will virtually retain all of the rigidity of a solid one-piece construction, and will possess the advantages of an insertable tooth formation which admits of the economies and also of 25 the use of superior metal in the cutting edges, and which from a structural standpoint will be of the utmost simplicity and will be free from all unnecessary elements.

Regarding the self-guiding feature, the 30 object of this invention is to make provision for the use of a so-called "pilot" which will be detachable so as to permit pilots of different diameters to be used in accordance with the particular size of the hole or recess to be 35 worked upon. It is of advantage, in adhering to the dictates of structural simplicity to use pilots having stems of standard size receivable in axial sockets in the end of the shaft. Since the head of the pilot should 40 fit the hole being worked upon rather closely and since it should turn in that hole, and since thereby a considerable friction is often created, the stem of the pilot may be subjected to considerable torque which would 45 tend to twist it off if the shank was used as the medium for rotating the pilot as a unit with the tool. This difficulty is overcome by the present invention through the expedient of providing the head of the pilot with shoulders for abutment against rigid portions of 50 the tool; the protruding side faces of the teeth being especially suitable for that purpose.

Other objects and advantages will be in

part indicated in the following description 55 and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts 65 throughout all the views of which:

Fig. 1 is a side-elevation of an adjustable counter-boring tool embodying all of the features of this invention. Fig. 2 is a bottom end elevation of Fig. 1. Fig. 3 is a side 70 elevation partly in section with the teeth omitted, showing the pilot alone attached to the shank. Fig. 4 is a top elevation of the pilot itself. Fig. 5 is a bottom end elevation of the shank itself with both the pilot 75 and the teeth omitted. Fig. 6 is a perspective of an isolated tooth and Fig. 7 is an enlarged elevation partly in section of a completely assembled tool.

Referring to the drawings, A denotes the 80 body portion of the tool which in this instance assumes the form of a shank having a conventional stem 1 adaptable for insertion in a taper-drill holder and having a head A' constructed as will be presently described. 85 B indicates one of a series of insertable teeth and C denotes a pilot.

When it is desired to have the adjustment previously indicated, the teeth are detachably inserted and this is accomplished by 90 providing the body portion A' with a series of slots 2, 3, 4, 5 etc., which figuratively speaking, extend radially when a peripheral series of cutting edges are to be desired. One face of each of these slots is preferably 95 arranged in coincidence with a plane extending parallel with the axis of the tool and such faces are each provided with a similar conformation A², which, in this instance, is shown as a corrugation or series of ridges 100 a, a', a'', a'''. An accurate identity is preserved in all respects except that the conformations are successively displaced slightly (say .005 of an inch) away from the axis; in other words, the points a, a', a'', and a''' are progressively a few thousandths of an inch further from the center. The significance of this characteristic is that if the iden-

tical tooth be inserted successively in each of the slots, it will protrude progressively further.

Referring to the tooth B shown by Fig. 6, 5 its rear face is flat except for corrugations or conformations B² which are the counterparts of those A² provided by the body portion or shank. These corrugations or conformations are parallel (in this instance) with the axis, 10 so that the end 7 of the tooth can be easily slipped into the open end of the slot and shifted parallel with the axis while the conformations A² and B² are interfitting.

For the purpose of cramping each tooth 15 firmly in its socket, the front face 8 of each tooth is at an angle with the rear face so as to produce a wedge-like shape, and the front face 6 of each slot is tapered at the same angle with respect to the rear corrugated face. 20 The slots are, as indicated by 9 preferably somewhat longer than the teeth to provide a sufficient degree of clearance and yield and the teeth are readily secured in place by driving them into the sockets in a direction 25 parallel with the axis until the yield and the friction prevent further movement.

The peripheral edges as well as the end edges of the teeth may then be ground and sharpened and the tool used until the teeth 30 become dull. Thereupon, by striking the protruding end edges 10 of the teeth, they may be driven out and replaced in the next adjacent sockets of the series which will result in shifting each tooth except the last outwardly to the extent of the increment between the successive conformations. The last tooth will then fall into the place of the first tooth and will be shifted a whole corrugation and in consequence it will protrude somewhat 35 40 more than the others because the corrugations will usually be wider than the sum of the increments. This extra protrusion of the last tooth could, of course, be ground off and the whole series ground down to the correct diameter and sharpened.

An important characteristic of this structure is that no extra fastening elements are necessary because the teeth hold themselves in by the wedging action and as the advance 50 of the tooth is in a direction contrary to the wedging action, the heavier the duty performed by the tool, the more surely will the teeth remain in place. For the purpose of chip clearance, it is desirable to provide a circumferential series of clearance grooves or 55 gouges 11 and a corresponding series of end face grooves 12 as will be readily perceived from the drawings.

With respect to the mounting of the pilots 60 C, the body portion is provided with a cylindrical co-axial hole 13 adapted to receive a stem 14 which is concentric with the head C' of the pilot C. For the purpose of holding this pilot against dropping out, a set screw 15 65 may be used but neither this set screw nor any

portion of the stem 14 is used to compel the pilot to rotate as a unit with the tool. That is accomplished by providing the head C' of the pilot with a series of shoulders 16 which overlap and hence will abut the side faces 8 70 of the ends of the teeth. The teeth thus act as propelling elements for the pilot and carry the torque necessary to cause it to rotate as a unit with the tool.

This construction has the pronounced ad- 75 vantage that pilots of various sizes for fitting any given hole can be readily inserted in the tool since the stems can be made small and of uniform size, and the head of the pilot irrespective of its size can be driven without fail inasmuch as it interlocks with the protruding portions of the teeth themselves which are, of course, of high grade material and of sufficient strength to accomplish that work. Furthermore, the torque is distributed 80 85 among all of the teeth and hence is not centralized on any.

It will thus be seen that this invention is well adapted for use either as a self-guiding tool alone or as an adjustable cutter tool alone, 90 or as an adjustable-tooth self-guiding tool for counter-bore work.

Without further analysis, the foregoing will so fully reveal the gist of this invention that others can, by applying current 95 knowledge, readily adapt it for various utilizations by retaining one or more of the features that, from the standpoint of the prior art, fairly constitute essential characteristics 100 of either the generic or specific aspects of this invention, and, therefore, such adaptations should be, and are intended to be, comprehended within the meaning and range of equivalency of the following claims.

Having thus revealed this invention, I 105 claim as new and desire to secure the following combinations and elements, or equivalents thereof, by Letters Patent of the United States:

1. In a counter-boring tool, the combination comprising a head portion; radial slots formed in said head portion, said slots having serrations formed in the sides thereof and the serrations in successive slots being set an additional amount away from the axis of the 110 tool corresponding to an increment of the distance between two serrations; detachable cutting blades adapted to fit in the slots in said head and having serrations interfitting the serrations in said slots; and a pilot having shoulders for engaging protruding portions of said blades to prevent it from turning relatively to the tool.

2. A rotary metal cutting tool comprising 115 a base portion providing a succession of sockets; a series of inserted cutting bits, each of said bits having a multiplicity of corrugations parallel with one of its cutting edges, and the successive sockets having interfitting corrugations progressively offset from the axis by 120 130

an increment of the distance between two serrations whereby upon shifting each of said cutting bits to the socket next advanced in the series, it will protrude to a slightly greater extent; and a pilot mounted in said tool, said pilot having its rear face formed to interlock with said bits and be thereby prevented from turning.

3. In a counter-boring tool, the combination comprising a head portion; slots formed in said head portion, each of said slots being wedge-shaped in the direction of the axis of said tool and having serrations formed on one side thereof, the serrations in successive slots being set away from the axis of the tool an additional amount equalling a small increment of the distance between two serrations; and detachable longitudinally wedge-shaped cutting blades adapted to fit in said slots, each blade having serrations formed in one side thereof for enabling the setting of the blades laterally away from the axis of the tool said small increment when moved from one slot to the adjacent slot.

25 4. In a metal cutting tool, the combination comprising a base having a plurality of slots formed therein around its axis; and a plurality of cutting blades for insertion in said slots, each of said blades having parallel serrations formed on one side thereof for interfitting similar serrations formed in the adjacent wall of each of said slots permitting removal of the blade by movement along the serration, and the serrations formed in successive slots being offset from the axis an additional amount equalling a small increment of the distance between two serrations.

5. A rotary cutting tool combining a body member; a series of blades openings therein; cutting blades shaped in accordance with said openings adapted to be inserted therein; a series of similar formations on a face of each blade; interfitting formations on the ad-

jacent wall of said body member, the formations on the said walls of successive openings being advanced an increment of the distance between two formations whereby the blade may be progressively advanced in accordance therewith by insertion in succeeding slots.

6. A rotary cutting tool combining a body member; a series of blade openings therein; cutting blades adapted to fit in said openings, said openings and blades being tapered to form a wedging fit for said blades; a series of similar interfitting formations on a side wall of each opening and the adjacent blade surface with the formations extending in the direction of the taper, the formations in each slot being offset with respect to the axis from the position in adjacent slots a small increment of the distance between two formations whereby the blade may be progressively advanced transverse to the taper by movement to succeeding slots.

7. A rotary cutting tool comprising a body member; a series of blade openings therein; cutting blades adapted to fit in said openings, said openings and blades being tapered in the direction of the axis of the tool to form a wedging fit for said blades; a series of similar interfitting formations on a side wall of each opening and the adjacent blade surface extending in the direction of the taper, the formations in the successive slots being distanced from the axis by an additional amount equal to a fraction of the distance between two formations; and a detachable pilot coaxial with the tool and having openings receiving the cutter bit ends including radial shoulders adapted to bear against said cutter bit ends, said openings permitting variation of both the radial and axial position of said blades.

In witness whereof, I have hereunto subscribed my name.

OLE SEVERSON.
